UNITED STATES PATENT OFFICE

JAMES M. DAVIS, OF SMACKOVER, ARKANSAS

PORTABLE STARTER FOR HEAVY INTERNAL-COMBUSTION ENGINES

Application filed September 27, 1929. Serial No. 395,731.

The present invention relates to a portable starter for heavy internal combustion engines and has for its prime object to provide a mobile structure of the automobile type with means incorporated therewith so that the same may be utilized in starting heavy internal combustion engines which are extremely difficult to crank.

Another very important object of the invention resides in the provision of a portable starter of this nature which is comparatively simple in its construction, easy to manipulate, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a top plan view of the apparatus embodying the features of my invention,

Figure 2 is a side elevation thereof,

Figure 3 is a detail sectional view taken substantially on the line 3-3 of Figure 1,

Figure 4 is a perspective view of a spring mount bar,

Figure 5 is a perspective view of a rod,

Figure 6 is a sectional view taken substantially on the line 6-6 of Figure 1, and

Figure 7 is a perspective view of a plate.

Referring to the drawings in detail it will be seen that the invention consists of a small or miniature automobile of narrow gauge denoted generally by the letter A, capable of travelling and proceeding by means of its own power, generated by gasoline, kerosene, naptha or any other combustible fuel engine or motor, (not shown) under a suitable hood 5.

The power generated by the engine is transmitted in the usual way to rear wheels 6 and 7 through the elements commonly known as transmission gears, transmission shafts, differential etc. On the right rear wheel 6 of this conveyance is attached and

rigidly held thereto by suitable means a friction pulley 2, the outer end of the pulley being provided with a reduced centrally located projection 3 which is free to rotate in bearing 4 on the adjacent end of the brace 35.

This brace 35 forms a part of frame 36 which is permanently secured to the conveyance by suitable means so that the frame 36 becomes a part of and moves with said conveyance at all times.

Extending through a tubular portion 40 of the frame 36 and disposed horizontally along the rear of the conveyance is a shaft 37 and secured to one end of this shaft 37 and depending therefrom is a lever 8 (see Figure 2). Fixed on the other end of the shaft 37 and extending upwardly therefrom is a lever 9.

When the heavy duty engine indicated in dotted lines in Figures 1 and 2 is to be started, the conveyance is driven alongside parallel to the engine base and the rear of the conveyance is then lifted and placed upon the rolling dolly truck 12.

A nut 13 is then removed from the foundation bolt 14 of the engine. A hinged strap 15 is placed over the bolt 14 and nut 13 is replaced and screwed down firmly.

A sliding member 42 including a rod 16 is adjustably connected with the lever 8, the member 42 being bifurcated and having a plurality of openings 17 so that a pin 43 may be inserted therethrough and through the extremity of the lever 8. Friction brake 18 is then applied to the left rear wheel 7 of the conveyance and is sufficiently tight to prevent the wheel 7 from revolving under normal strain. The motor of the conveyance is started up, and the lever 11 is pulled toward the rear of the conveyance which in turn pulls rod 10 and lever 9 forwardly.

The shaft 37 is rocked thereby causing arm 8 to pull sliding member 16 thereby creating a tension on compression spring 20. This compression spring 20 is disposed between the rearmost of a pair of ears 43 rising from the hinged base 21 and a collar 23 on the rod 16, this rod 16 being slidable through openings in the ears 43.

The hinged base 21 of course, is hingedly connected with the strap 15. The spring 20, in an effort to resist compression, draws the conveyance on the rolling truck 12 slightly forward thereby frictionally and resiliently engaging the pulley 2 with the engine fly wheel 23 thereby causing the fly wheel 23 to revolve.

The engineer, of course, may then regulate the fuel supply, ignition, etc., of the heavy engine until the same starts. When the heavy engine starts, the lever 11 is then released thereby relieving frictional engagement of pulley 2 and fly wheel 23. The strap 15 is then removed and the dolly truck 12 is removed from under the conveyance. The work may thus be accomplished by one man instead of several as are often required and without risk of life and limb as compared with the present method of revolving heavy engine fly wheels by hand.

It is thought that the construction, operation, utility and advantages of the invention will now be quite apparent to those skilled in this art without a more detailed description thereof.

The present embodiment of the invention has been disclosed in considerable detail merely for the purpose of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In combination, an automobile conveyance including a pair of rear drive wheels, mobile means associated with the conveyance for holding said drive wheels raised from the ground, a pulley on one of the drive wheels, a brake for the other drive wheel, and manually operable resilient means for shifting the conveyance in a manner to operatively engage the pulley frictionally with an engine fly wheel, said means including an anchoring device, a lever, and means for adjustably connecting the lever to the anchoring device.

2. In combination, an automobile conveyance comprising a pair of rear drive wheels, mobile means for holding said conveyance raised with the drive wheels off the ground, a pulley on one drive wheel, a brake on the other drive wheel, a frame, means for attaching the frame to the conveyance, a shaft rockable in the frame, a crank on the shaft, resilient connecting means between the crank and the base of an engine to be cranked, and means for rocking the shaft to tension the connecting means to urge the conveyance in

a direction to resiliently and frictionally hold its pulley against the fly wheel of the engine to be cranked.

3. In combination, an automobile conveyance comprising a pair of rear drive wheels, mobile means for holding said conveyance raised with the drive wheels off the ground, a pulley on one drive wheel, a brake on the other drive wheel, a frame, means for attaching the frame to the conveyance, a shaft rockable in the frame, a crank on the shaft, resilient connecting means between the crank and the base of the engine to be cranked, and means for rocking the shaft to tension the connecting means to urge the conveyance in a direction to resiliently and frictionally hold its pulley against the fly wheel of the engine to be cranked, said connecting means comprising a pair of hingedly connected members one anchored to the base and the other having a pair of ears rising therefrom, a rod slidable through the ears, a spring on the rod between the ears impinging against one ear and a collar on the rod, one end of the rod being bifurcated and provided with a plurality of openings, and a pin extending through one of the openings and through the crank.

In testimony whereof I affix my signature.

JAMES M. DAVIS.
